CLAIM

The ornamental design for a bottle brush, as shown and described.

DESCRIPTION

FIG. 1 is a front, right, and top perspective view of a first embodiment of a bottle brush, showing our design.

FIG. 2 is a front elevation view of the bottle brush of FIG. 1.

FIG. 3 is a rear elevation view of the bottle brush of FIG. 1.

FIG. 4 is a left side elevation view of the bottle brush of FIG. 1.

FIG. 5 is a right side elevation view of the bottle brush of FIG. 1.

FIG. 6 is a top plan view of the bottle brush of FIG. 1.

FIG. 7 is a bottom plan view of the bottle brush of FIG. 1.

FIG. 8 is a partial enlarged view of an area labeled 8 in FIG. 1 comprising a part of bristles.

FIG. 9 is a front, right, and top perspective view of a second embodiment of a bottle brush, showing our design.

FIG. 10 is a front elevation view of the bottle brush of FIG. 9.

FIG. 11 is a rear elevation view of the bottle brush of FIG. 9.

FIG. 12 is a left side elevation view of the bottle brush of FIG. 9.

FIG. 13 is a right side elevation view of the bottle brush of FIG. 9.

FIG. 14 is a top plan view of the bottle brush of FIG. 9.

FIG. 15 is a bottom plan view of the bottle brush of FIG. 9.

FIG. 16 is a partial enlarged view of an area labeled 16 in FIG. 9 comprising a part of bristles.

FIG. 17 is a front, right, and top perspective view of a third embodiment of a bottle brush, showing our design.

(Continued)

FIG. 18 is a front elevation view of the bottle brush of FIG. 17.

FIG. 19 is a rear elevation view of the bottle brush of FIG. 17.

FIG. 20 is a left side elevation view of the bottle brush of FIG. 17.

FIG. 21 is a right side elevation view of the bottle brush of FIG. 17.

FIG. 22 is a top plan view of the bottle brush of FIG. 17.

FIG. 23 is a bottom plan view of the bottle brush of FIG. 17.

FIG. 24 is a partial enlarged view of an area labeled 24 in FIG. 17 comprising a part of bristles.

FIG. 25 is a front, right, and top perspective view of a fourth embodiment of a bottle brush, showing our design.

FIG. 26 is a front elevation view of the bottle brush of FIG. 25.

FIG. 27 is a rear elevation view of the bottle brush of FIG. 25.

FIG. 28 is a left side elevation view of the bottle brush of FIG. 25.

FIG. 29 is a right side elevation view of the bottle brush of FIG. 25.

FIG. 30 is a top plan view of the bottle brush of FIG. 25.

FIG. 31 is a bottom plan view of the bottle brush of FIG. 25; and,

FIG. 32 is a partial enlarged view of an area labeled 32 in FIG. 25 comprising a part of bristles.

The long-short-long broken lines in the drawings illustrate the bounds of the portions of FIGS. 1, 9, 17 and 25 that are

then shown in the enlarged views FIGS. 8, 16, 24 and 32. The long-short-long broken lines form no part of the claimed design.
